UNITED STATES PATENT OFFICE.

JOHN RIDDELL, OF SCHENECTADY, NEW YORK, ASSIGNOR OF ONE-FIFTH TO
ALEXANDER F. MACDONALD, OF SAME PLACE.

GRADE-DELINEATOR.

SPECIFICATION forming part of Letters Patent No. 624,866, dated May 9, 1899.

Application filed April 15, 1898. Serial No. 677,665. (No model.)

To all whom it may concern:

Be it known that I, JOHN RIDDELL, a citizen of the United States, residing at Schenectady, in the county of Schenectady, State 5 of New York, have invented certain new and useful Improvements in Grade-Delineators, of which the following is a specification.

My invention relates to that class of machines which are employed to delineate the 10 profile of a path traveled over.

In my pending application, Serial No. 615,985, filed December 17, 1896, I have described and claimed a machine for delineating the profile of a path traveled over in 15 which the marker is mounted on an oscillating frame and is free to travel back and forth thereon as the actuating-pendulum changes its position with respect to the machine, due to changes in the grade.

20 I have found that in machines similar to the one described, which depend for their action upon a swinging pendulum, there is always a certain amount of lost motion between the pendulum and the marker-support and that this lost motion becomes more 25 marked as the parts wear. This would not be so objectionable if the grades were all one way, as the machine could be properly calibrated, but where the machine is intended 30 for all kinds of grades, rough or smooth, it introduces errors into the readings of the instrument. I have also found that a machine 35 will not give the same reading when started at the top of a hill and worked down as when started at the bottom and worked up, due to the same cause.

My invention has for one of its objects to 40 provide a machine which will accurately record the profile of a path traveled over with out regard to the direction in which the machine travels, whether it be up or down grade.

My invention further has for its object to 45 improve the construction and general arrangement of the machine, as set forth in the claims.

In the accompanying drawings, which show 50 an embodiment of my invention, Figure 1 is a side elevation of a profile-delineating machine. Fig. 2 is a plan view of the same. Fig. 3 is a side elevation of the marker-frame. Fig. 4 is a side elevation of a bicycle with the machine operatively attached thereto. Fig.

5 is a sectional detail, and Fig. 6 is a modification of the marker.

The frame of the machine consists of two 55 flat plates A and A', which are separated and held in position by the rods B and B', and also by the shafts C' and D' of the reel C and the drum D. The paper or other recording surface I is mounted on the reel C and is 60 passed over the drum D to the reel E, in a manner hereinafter described. Secured to the side plate A' is a curved arm F, which carries the oscillating marker-frame G. The arm is provided with a vertical portion F', 65 which furnishes a bearing for the vertical stem G' of the marker-frame. At the upper end of the portion F' is mounted a yoke F², into which the ends of a flat spring F³ are inserted. Mounted on the spring is a body of 70 metal, which furnishes a support for the adjusting-screw a, and to lock the screw in place a check-nut a' is provided. By adjusting the vertical height of the screw a the tension on the spring is changed and the marker H will 75 make a greater or less impression upon the recording-surface.

The marker-frame is forked on its lower side, and mounted in the arms of the fork is a cylindrical shaft G³, upon which the marker 80 H is free to travel back and forth in an unobstructed manner. One end of the frame is grooved, and mounted therein is an adjustable loose-fitting arm J, having a thickened portion at one end to form a bearing and a 85 set-screw G² at the other for securing the flexible connection T, which connects the marker-frame with the pendulum Q. Situated on each side of the arm are adjusting-screws J². These are so arranged that the position of the 90 marker-frame and the indicator X, carried thereby, may be brought to the zero position on scale X', the latter being secured to the side frame A. There being a certain amount of spring in the arm J considerable adjustment may be obtained, although it is not intended to make any very decided adjustments at this point, the larger adjustments being made by changing the length of the flexible connection T either side of a central 95 position.

The marker H consists of a cylindrical body of metal having an extended hub H' to give it a sufficient bearing on the shaft G³. The

central portion of the marker is provided with a circular knife-edge H^3 , which is serrated for perforating or marking the recording-surface I. The marker is free to travel back and forth on the shaft G^3 , and will, when the marker-frame is set at an angle to its normal plane, travel across the recording-surface and record the profile of the path traveled over. By properly adjusting the parts the marker may be made to record changes in vertical heights at the same scale as the linear distances, but as the changes in altitude are comparatively small with respect to the distances traveled over it is preferable to make the vertical scale greater than the horizontal; but in either event the record made by the machine is direct-reading and requires no calculation to determine the profile of the path.

Mounted on flat springs K are pencils K' , which are employed to rule the reading-surface I, although ruled paper may be substituted for the plain and the pencils dispensed with. The pencils, instead of being in the same straight line, are so arranged that they occupy positions nearer the support K^2 as they leave the center. This is to permit the oscillating frame G to have a wide range of movement without increasing the length of the machine.

The springs K are mounted in the support K^2 , which is supported by the side plates A and A' of the frame. The support K^2 is pivotally secured in place, and a nut K^3 is employed to regulate the tension on the springs K by clamping the support in various positions. If desired, the support may be rotated backward until the pencils are out of contact with the paper and locked by the nut while in that position. In order to give the proper tension to the paper, the reel D is provided with an adjustable friction-brake L, which operates on the hub of shaft D'.

Referring to Fig. 5, the arrangement of the parts employed for moving the paper is clearly shown. The paper on leaving the reel D passes upward over the marker-table M, and thence partially around the positively-driven drum C and the spring-pressed drum N to the reel E. The shaft of drum N is mounted in spring-pressed blocks N^3 , which move up and down in guides N^4 , located on the outside of the frame-plates. The pressure of the drum on the paper I and belt P is regulated by means of the spring N' and the adjusting-screws N^2 .

I have found that where the marker-table M is covered with a fixed piece of leather or similar material to form a cushion it soon becomes filled with small perforations or grooves, due to the marker II, and that it requires a considerable movement on the part of the pendulum to withdraw the marker from said grooves or perforations. To overcome this difficulty, I employ a belt P, made of leather or other material having a firm texture, yet being soft enough to act as a pad or cushion for the marker. One end of the belt

is arranged to pass over the pulley P' and the other end over the drum C.

Mounted on the frame of the machine or on a separate support is a reel E, which winds up the paper after the record has been made thereon. This I have found to be a particularly desirable feature, for it enables me to remove the old record and substitute a reel of paper with but slight difficulty, and, moreover, the record is open to inspection as it moves along. Situated on one side of the reel is a pulley E', (shown in dotted lines,) and running around this pulley and a corresponding pulley C² on the drum C is a belt O. The pulley on the drum being a trifle longer than the one on reel E the latter will tend to travel faster than the drum, but this being prevented by the paper the belt will slip slightly and a tension on the paper will be maintained at all times and practically without regard to the diameter of the rolls of paper on the reel. On the end of the drum C is mounted a wheel W⁴, and meshing therewith is a worm W³, that is formed on the upper end of the rod W². The rod W² is supported at its lower end by a suitable bearing W⁵, which is mounted on the frame of the bicycle. The lower end of the rod is provided with a worm W', which meshes with a worm-wheel W, carried by the rear wheel. The drum being positively geared to a moving wheel of the vehicle, it will cause an amount of paper to be unwound from the reel corresponding to the distance traveled over. I have found a scale of twenty inches to the mile to be very satisfactory.

I have found that to make a machine of this character register accurately at all times it is necessary to avoid connections between the marker and the pendulum which are liable to lost motion—as, for example, the ordinary pin-and-slot connection. To overcome this, the pendulum Q is connected to the marker-frame by means of a flexible connection—as, for example, a cord or wire T. Thus, the weight being directly connected to the marker-frame instead of being supported by a pivot, there is no chance for lost motion, the pendulum itself taking up all slack or looseness. Mounted on the ends of the frame-rods B and B' are sets of pulleys R and R', and mounted in the pendulum Q are corresponding sets of pulleys Q' and Q², the several sets uniting to form a differential-pulley system. The central portion of the cord T is secured to the marker-frame by the adjusting thumb-nut G², and one end passes over one of the pulleys in set R, thence around one of the pulleys in set Q', and so on until the proper number of turns have been made, after which the end of the cord is secured, as at U. The opposite end of the cord passes around the pulleys R' and Q² in a similar manner and is secured at U'. I have shown three pulley-wheels in each of the upper sets, although only two of them are employed; but it is evident that I may employ a greater or less number without depart-

ing from my invention. The pendulum being suspended entirely by the flexible connection T, which is connected to the marker-frame G, the latter is not permitted to move except when the pendulum moves. The arrangement of the pulleys, weight, and marker is such that the marker is always brought to the same position each time the pendulum moves a certain definite amount, without regard to whether the machine is moving up or down grade.

To prevent the pendulum from swinging laterally, a pivoted guide V is employed, which extends through the body of the weight and is provided with a nut at its lower end to prevent the weight from dropping in case the cord T breaks. The weight and movement of the pendulum are entirely independent of the guide V, except in so far as the latter is prevented from swinging across the path of travel. No means are shown for adjusting the cord T, as it is deemed unnecessary, as any one of a number of well-known devices may be employed.

The operation of the machine is as follows: Motion being transmitted to the drum C by means of the worm-wheel W, worm W', rod W², worm W³, and worm-wheel W⁴, the paper is withdrawn from reel D at a rate depending upon the speed at which the bicycle is driven. So long as the profile of the path is level the marker H will make a straight mark or a series of small perforations; but as soon as the profile changes either up or down the pendulum will cause the marker-frame to be deflected a greater or less amount from the position shown and the marker will travel across the paper at an angle, the amount depending upon the deflection of the pendulum. As soon as the bicycle reaches a level portion of the path the pendulum will set the marker straight again; but so long as the bicycle maintains its present elevation the marker will keep its distance from the center line of the starting-point. It is only after the bicycle has gone down a grade corresponding in degree to the one it went up that the marker will return to the line of its first position.

By arranging the marker H loosely upon the oscillating frame and permitting it to move freely thereon I am enabled to make a record of the path traveled over, which is direct-reading—that is to say, the profile is indicated thereon—and not a series of points or lines from which it is necessary to calculate in order to obtain even an approximate idea of the profile.

When the vertical scale of the machine is such that the marker is about to run off the paper while traveling on a grade, it is only necessary to slide the marker bodily on the shaft G³ from one edge of the paper to the other and the machine will register as before. When the record is removed from the machine, it can be cut at the places where the marker was shifted, the ends of the indications matched, and the parts of the record

pasted together. By this arrangement the machine has a practically unlimited range of operation in the vertical plane and it is a simple matter to supply new rolls of paper for the horizontal plane.

In Fig. 6 I have shown a modification of the marker H on a somewhat-enlarged scale. The marker is so arranged that it will make a certain number of revolutions for each mile traveled, and to facilitate reading the record one or more special teeth h are cut on the marker, so that once in so often—say every eighth of a mile—a perforation is made which differs 80 from the adjacent ones. This is particularly useful where the paper is only ruled longitudinally.

I have shown my invention in connection with a bicycle, as this represents the cheapest 85 and simplest form of construction; but for certain classes of work where greater accuracy is required and additional weight no objection I make the parts of the machine larger and mount it upon a different type of vehicle—as one having four wheels, for example.

What I claim as new, and desire to secure by Letters Patent of the United States, is—

1. In a machine for profiling a path traveled over, the combination of a marker-frame, 95 a marker mounted thereon, a pendulum, and a flexible connector between the pendulum and the marker-frame which sustains the pendulum.

2. In a machine for profiling a path traveled over, the combination of a marker-frame, 100 a marker mounted thereon, and capable of independent movement, a pendulum, and a flexible connector between the pendulum and the marker-frame which sustains the pen- 105 dulum.

3. In a machine for profiling a path traveled over, the combination of a marker-frame, 110 a marker mounted thereon, means for changing the position of the marker when the profile of the route changes, and a flexible connector between said means and the marker-frame which sustains the pendulum, whereby lost motion between them is prevented.

4. In a machine for profiling the path of a 115 route traveled over, the combination of an oscillating support, a marker sleeved on the support in such manner that it is free to rotate and also to move laterally, means for causing the lateral movement of the marker, 120 and a flexible connection between the said means and the support for the marker.

5. In a device for profiling a route traveled over, adapted to be mounted on a vehicle and operated thereby, the combination of means 125 for continuously moving the recording-surface as the vehicle progresses, a rotary marker, a support upon which the marker is free to rotate and also to move laterally, the arrangement being such that the marker may rotate 130 without moving laterally or both motions may take place simultaneously, depending on the profile of the route traveled over, means for changing the position of the support as

- the profile of the route varies, whereby the marker is permitted to travel laterally along its support and across a recording-surface at an angle and indicate the profile of the route, 5 and a flexible connector between said means and the support for preventing lost motion.
6. In a machine for profiling a path traveled over, the combination of a marker, a support therefor, a pendulum, and a cord for suspending the pendulum, and also for connecting it to the support for the marker.
7. In a machine for profiling a path traveled over, the combination of a marker, a support therefor, a flexible connector, and a pendulum which is suspended from the machine by the flexible connector, which connector also serves to transmit motion from the pendulum to the marker.
8. In a machine for profiling a path traveled over, the combination of a marker, a support therefor, pulley-wheels mounted on the frame of the machine, a pendulum, pulley-wheels mounted on the pendulum, and a flexible connector which runs over the pulley-wheels and sustains the weight of the pendulum.
9. In a machine for profiling a path traveled over, the combination of a pendulum for actuating the moving parts of the machine, 30 and a flexible connector for sustaining the weight of the pendulum.
10. In a machine for profiling a path traveled over, the combination of a pendulum for actuating the moving parts of the machine, 35 a flexible connector for sustaining the pendulum, and a guide which prevents lateral movement of the pendulum, but permits free longitudinal movement.
11. In a machine for profiling a path traveled over, the combination of a pendulum for actuating the moving parts of the machine, 40 a flexible connector for supporting the pendulum, and means for supporting the pendulum in case the flexible connector breaks.
12. In a machine for profiling a path traveled over, the combination of an oscillating marker-frame, a marker mounted thereon, a pulley-wheel situated on each side of the marker-frame, a pendulum, a flexible connector extending over the pulleys to sustain 45 the pendulum and connected to the marker-frame at a point distant from its center of movement.
13. In a machine for profiling a path traveled over, the combination of an oscillating marker-frame, a marker mounted thereon, a pendulum, an adjustable extension-arm on the marker-frame, and a flexible connector between the pendulum and the arm.
14. In a machine for profiling a path traveled over, the combination of an oscillating marker-frame, a marker mounted thereon, and capable of independent movement, a yoke 50 carried by a fixed part of the machine, and a flat adjustable spring mounted in the yoke 65 for pressing the marker-frame into engagement with a recording-surface.
15. In a machine for profiling a path traveled over, the combination of a reel upon which the recording-paper is mounted, a pivoted support, a plurality of flat springs mounted in the support, each provided with a marking device, and means for securing the pivoted support in any desired position.
16. In a machine for profiling a path traveled over, having a movable recording-surface, the combination of a marker, a table under the marker, and a moving pad or cushion between the marker and the table.
17. In a machine for profiling a path traveled over, having a movable recording-surface, the combination of a marker, a table under the marker, and a positively-driven pad or cushion moving over the table.
18. In a machine for profiling a path traveled over, having a movable recording-surface, the combination of a marker, a fixed table under the marker, and a positively-driven endless belt which acts as a cushion or pad.
19. In a machine for profiling a path traveled over, the combination of a reel upon which the recording-paper is mounted, a drum over which the paper passes, and a leather belt which is driven by the drum, which acts as a cushion.
20. In a machine for profiling a path traveled over, the combination of a reel upon which the recording-paper is mounted, a drum over which the paper passes, a belt which is 90 driven by the drum, which acts as a cushion, and means for maintaining the proper tension on the belt.
21. In a machine for profiling a route traveled over, the combination of a marker, with 95 a pendulum for moving the marker, which is connected to the marker and suspended from the machine by a flexible connector.
22. In a machine for profiling a route traveled over, the combination of a marker, a frame therefor which is slotted at one end, an arm mounted in the slot, and adjusting-screws for moving the arm.
23. In a machine for recording the profile of a route traveled over, the combination of 105 a rotary marker having a serrated marking edge, with one or more of the serrations made of a different shape, for indicating given distances.

In witness whereof I have hereunto set my hand this 12th day of April, 1898.

JOHN RIDDELL.
